UNITED STATES PATENT OFFICE.

GEORGE BROWNING, OF WILMETTE, ILLINOIS, ASSIGNOR TO CHICAGO FLEXIBLE SHAFT COMPANY, OF CHICAGO, ILLINOIS, A CORPORATION OF ILLINOIS.

ADJUSTABLE NOZZLE.

Application filed June 22, 1925. Serial No. 38,665.

The purpose of this invention is to provide an improved form of nozzle particularly adapted for use in lawn sprinklers, and designed with a view to economy of manufacture, and simplicity in adjustment. It consists of certain features and elements of construction as herein shown and described, and as indicated in the claims.

In the drawings:

10 Figure 1 is a side elevation of a portable lawn sprinkler standard of the rotating arm type, fitted with two similar nozzles embodying this invention.

15 Figure 2 is a vertical medial section showing one of the nozzles as adjusted to throw a wide spray.

Figure 3 is also a medial section of the nozzle showing a valve adjusted to throw a coarser stream.

20 While it may be understood that the features of this invention are not limited to the nozzle used in a lawn sprinkler, I have chosen this device for purposes of illustration, and in Figure 1, I have shown the 25 sprinkler base, 1, upon which a hub, 2, is rotatively mounted with its rigid radial arms, 3, through which the water is conducted to the nozzles mounted in the threaded terminals, 4, of the arms. Each nozzle is attached by means of its threaded base nipple, 5, to which the upright inlet stem, 6, is 30 screwed.

The stem, 6, provides a lateral inlet for the water into the barrel, 7, at a point between its ends and the barrel is bored through from end to end. At the discharge end it is formed with an inturned flange, 8, through which the head, 9, of the valve member, 10, is slidably adjustable. Back 35 of the head, 9, the valve member is reduced at 11 to provide space for the water in the chamber, 12, of the barrel. The rear end of the barrel opposite the discharge end is counter-bored to a slightly larger diameter 40 than the chamber, 12, and a retaining bushing, 13, is forced into place against the shoulder, 14, so as to engage the flange, 15, of the valve member to prevent the latter from being lost out of the barrel. Preferably, a washer of packing material, 16, is 45 inserted back of the bushing, 13, and a second bushing, 17, is forced in to fill the remaining length of the counter-bored portion. The bushings, 13 and 17, are bored to fit 50 snugly the stem of the valve member, 10,

and the rear end of said member is accessible for adjustment outside the barrel, being preferably provided with a knob, 18, which may be permanently attached, and forms a head for limiting the forwardly thrust position of the valve member, as shown in Figure 2.

The rear or outer end of the bushing, 17, is counter-bored and threaded at 19 to receive a threaded split bushing, 20. The forward end of the bushing, 20, is tapered at 21, to co-operate with the inclined shoulder, 22, of the bushing, 17, so that as the part 20 is screwed inwardly against the inclined shoulder, 22, its split portion will be forced into clamping engagement with the stem of the valve member, 10, for holding it at any adjusted position. This clamping engagement may be effected by a partial turn of the knurled head, 23, of the bushing, 20, or 75 the valve may be released by a similar movement in the opposite direction. Thus, the nozzle may be very quickly and easily adjusted for throwing the desired form of spray or stream, since the valve head, 9, may 80 be set at any point in its range, merely by a longitudinal sliding movement of the valve member, 10.

It will also be noted, that with the exception of the cast nozzle body, the parts are 85 all simple cylindrical forms which may be cheaply and rapidly produced on an automatic screw machine or the like, thus rendering the construction economical to manufacturer.

I claim:

1. In a nozzle the combination of a barrel bored through from end to end and provided with a lateral inlet intermediate its ends, a valve member having a portion adjacent one end of the barrel for controlling discharge therefrom, and a portion accessible beyond the other end of the barrel for adjusting said member, said other end of the barrel being counterbored to form a shoulder, a bushing fitted around the valve member against said shoulder, and a second bushing inserted adjacent the first with packing material between said bushings, said second bushing being counterbored at its outer end 95 and formed with an inclined shoulder at the inner end of the counterbore, and a split bushing screwed into the counterbore of the second bushing and having a tapered end 100 portion engaging the inclined shoulder, to- 110

gether with means on the split bushing outside the barrel for adjusting it to force said tapered end portion against the inclined shoulder for clamping the valve member to 5 retain it in adjusted position.

2. In a nozzle in combination with a barrel having a bore extending from end to end with a discharge opening at one end and a transverse shoulder intermediate the ends of 10 the barrel, together with a lateral inlet entering the barrel between the discharge opening and said shoulder, a valve member having a portion at one end to co-operate with the discharge opening, and a stem portion

extending beyond the other end of the barrel, packing material around said stem, and a bushing inserted through said other end of the barrel snugly fitting said stem for forcing the packing against said shoulder, 15 said bushing being counterbored at its outer end and threaded, its counterbore forming an inclined shoulder at the inner end of the counterbore, and a split bushing threaded to fit the counterbore and having a tapered part to engage the inclined shoulder for compressing the split bushing into clamping engagement with the valve stem. 20 25

GEORGE BROWNING.
